BURIAL VAULT

James W. Prince, Parsons, Kans.

Application September 29, 1934, Serial No. 746,182

5 Claims. (CL 72—7)

This invention relates to improvements of burial vaults or cases particularly of the type which may be completely embedded in the ground or which may be placed above the surface of the ground and prevent the admission of water and air to the interior of the casing.

The primary object of this invention, is to provide a burial vault constructed in such a manner as to form a complete water and air proof receptacle for the purpose specified.

A further object of this invention, is to provide a vault or burial case having a lid adapted to be locked in place by the same reinforcing wires of the casing which wires also retain sections of the casing in spaced relations.

A further object of this invention, is to provide a burial vault having moisture collecting pipes embedded therein which serve to maintain the interior of the casing in a dry condition.

A still further object of this invention, is to provide a burial vault or casing including two lower compartments and having a lid upon which is formed a single compartment whereby two or more caskets may be preserved in a unitary structure.

A still further object of this invention, is to provide absorbent material in the bottom of the casing for the purpose of absorbing moisture, said absorbing material being retained in place by transverse ribs formed in the bottom wall of the casing, these ribs forming supports for the casket or coffin placed in the vault.

Heretofore, burial vaults have been formed of concrete but it has been found that such vaults after use are subjected to strain due to settling conditions occurring after the vault has been placed therein which settling conditions cause cracks to occur throughout the vault and entirely defeat the purpose for which the vault was intended.

By providing a structure including outer and inner shells of concrete and a central core formed of initially plastic waterproof material tied by reinforcing wires to the outer and inner shells of concrete such objections are overcome, because should one of the concrete sections become cracked through warping, said plastic inner wall will still retain atmospheric conditions and prevent the admission of water or air to the interior of the vault. It will thus be obvious that though the outer concrete wall may crack in one location and the inner wall may crack in another location at a distance from the first crack however, water and air will not be allowed to enter

the vault by reason of the intermediate ceiling plastic wall.

Other objects and advantages of the invention, will become apparent during the course of the following description forming a part of this specification and taken with the drawings wherein:

Figure 1 is a vertical sectional view of a burial vault embodying this invention.

Figure 2 is a vertical cross-sectional view enlarged illustrating an end portion of the vault 10 shown in Figure 1.

Figure 3 is a transverse cross-sectional view illustrating a modified form of the invention showing two or more casket containing compartments formed in a compact unit.

Figure 4 is a fragmentary cross-sectional view enlarged and illustrating a portion of the vault and illustrating an arrangement of the air tubes extending through the burial vault and

Figure 5, a vertical cross-sectional view taken 20 on lines 5—5 of Figure 3 looking in the direction of the arrows illustrating the manner in which the air tubes extend through the concrete wall casing so that the ends thereof are open to the atmosphere.

In the drawings, wherein for the purpose of illustrating this invention and wherein like reference characters will be employed to designate like parts of the same, the reference character 5 will generally be employed to designate an inner 30 container or shell formed of concrete and having embedded wire reinforcing members 6 to which are connected laterally extending reinforcing wires 7. The lateral reinforcing wires 7 may be welded or otherwise secured to the embedded 35 wires 6 and said laterally extending wires 7 are adapted to extend beyond the outer wall of the inner concrete container 5.

The inner concrete container 5 is preferably formed so as to provide transverse ribs 8 which 40 are adapted to form rests for a coffin 9 as shown in Figure 1. After the inner shell 6 is formed the outer surface of the inner shell 5 is completely covered with a layer of plastic material 10, the lateral reinforcing wires 7 protruding beyond 45 the surface of the plastic material 10.

Before the plastic material 10 has become completely hardened and after vertical and horizontal reinforcing wires 11 have been secured to the adjacent ends of the lateral reinforcing 50 wires 7 a coating 12 of concrete is placed over the plastic mass 10 so that the vertical and horizontal reinforcing wires 11 connected to the lateral reinforcing wires 7 will be embedded therein.

It must be noted that the vertical reinforcing wires 6 and 11 extend above the upper surface or edge of the side and end walls of the casing as shown as at 13 for the purpose of engaging 5 with transverse locking wires 14 and 14a for a purpose which will be hereinafter described.

The casing above described is provided with a lid including an outer concrete casting 15 having downwardly extending marginal portions in which is embedded horizontal reinforcing wires 16 to which are welded vertical reinforcing wires 17. After outer section 15 has been formed, it is partially filled with a plastic composition 18. The horizontal reinforcing wires 19 may be welded or otherwise engaged with or attached to the vertical reinforcing wires 17. The concrete section 15 may then be filled with a layer of concrete 20 so that the concrete section 20 will be flush with the overturned edges 16 of the top section 15.

The plastic material at 10 and 18 is of such consistency as to allow the cover 15 to be placed on the casing while the material at 10 and 18 is still plastic whereby the transverse anchoring wires 14 and 14a become set within the plastic material 18 formed between the concrete section 20 and the overturned edge 16 when the cover 15 is placed on the body of the vault thereby completely locking the cover in place with respect to the body.

After a period of time the plastic material 10 and 18 will become hardened and during this time the concrete section 15 and 20 will be held in spaced relation by means of the respective reinforcing wires 6, 7, 11 and 16, 17 and 20.

The lid 15a shown in Figure 3 is formed of cement in the same manner as that shown in Figures 1 and 2 but with inner and outer upstanding wall sections 21 and 22. These walls define an upper compartment for receiving a third casket, this upper compartment having its walls integral with the lid of the body of the vault. The body of the vault is divided into two compartments 29 and 30 by means of an intermediate wall 26 reinforced by the vertical wire 27 and the cross wires 28. The walls of the upper compartment 36 have the vertical reinforcing wires 22 and the transverse ties or connecting wires 23. These outer and inner shells are spaced apart and the space between these shells is filled with plastic waterproof material 25. The lid of this upper compartment 36 is of the same general construction as the lid shown in Figure 2 and it is to be understood that the vertical wires 22 in the walls of the compartment 36 extend up into the plastic material of the lid in the same manner as heretofore described.

The single cover 15a provided for the vault is identical with the casing cover shown in Figures 1 and 2 only sufficiently large to cover both chambers 29 and 30 and as shown in Figure 3 the cover 15a may be formed with the additional casing which is also provided with a lid constructed in identically the same manner as lid shown in Figure 2 and including an outer layer of concrete 15 and an inner layer of concrete 20 separated by an intermediate layer of plastic material 18 all of which is connected by the reinforcing wires 16, 17, and 19.

70 In Figures 3, 4 and 5 is illustrated a modified form of the invention contemplating the use of horizontal air tubes embedded in the inner concrete wall 6 and extending from one end of the
75 casing to the opposite end so that the free ends 31 are open to the atmosphere as shown in Figure 5.

In Figure 3 the partition 26 is provided with longitudinal pipes 31 to extend from end to end of the casing in the same manner as the pipes 31 which are embedded in the side walls 5 of the casing. The air tubes are adapted to extend longitudinally of the casing and preferably are embedded only partly in the side wall in any desired location so that such tubes are exposed to the interior of the casing through a longitudinal slot 32 formed in the interior side wall 6 as best shown in Figure 4. 10

In this manner, the air may circulate through the tube 31 and said air will cause a condensation of moisture within the casing which will be collected on the outside of pipe 31 through the slot 15 32 whereby the moisture content within the casing will be materially reduced.

Material having high absorptive qualities may be placed in the bottom of the casing as shown in Figures 1 and 2 at 33. Cellulose is a material which may be used for this purpose. The material shown at 33 may also be placed in the same manner in the casing shown in Figure 3 inasmuch as the bottoms of these three compartments are provided with the transverse ribs 8 and 8a 25 between which the absorptive material may be placed.

It is to be understood, that the form of the invention herewith shown and described is to be taken as a preferred embodiment of the claim 80 and that various changes in shape and size and arrangements of parts may be resorted to without departing from the spirit of the invention or the scope of the subjoining claims.

I claim:—

1. A burial vault, comprising inner and outer spaced concrete casings, reinforcing wires embedded in the concrete casings forming spacing members for the casings, a plastic mass filling the space between the casings, a lid for the casing including spaced concrete slabs, one of said slabs having an overturned edge to form a marginal recess, a plastic mass interposed between the slabs and in the marginal recess, the upper ends of the casing reinforcing members for being received in the marginal recess and anchored in the plastic material therein.

2. A burial vault, comprising an airproof casing, a lid for the casing and pipes partially embedded in the walls of the casing and having the outer ends open to the atmosphere, walls of the vault having slotted openings therein whereby certain portions of the pipes are exposed to the interior of the casing for the collection of condensation. 55

3. A burial vault comprising inner and outer spaced concrete shells in nested relation, a plastic material interposed between the concrete shells, cover for the burial case, and pipes embedded in the inner shell having their open ends extending through the walls of the case and open to the atmosphere and said inner shell having slots exposing portions of the pipes to the interior of the burial casing. 60

4. A burial vault comprising inner and outer spaced concrete shells, an intermediate layer of initially plastic material between the shells, a lid for the vault comprising inner and outer shells and an intermediate layer of plastic material, reinforcing members embedded in the outer and inner shells of the vault and extending above the side and end walls thereof, said reinforcing members being thus adapted to be embedded in the intermediate plastic material of the lid when the 75

lid is put in place to thus interlock the lid integrally to the body of the vault.

5. A burial vault including a body section having an outer concrete shell, an inner spaced concrete shell, vertical reinforcing members disposed within the side and end walls of the outer shell and inner shell, transverse reinforcements extending through a space between the shells and connected to the vertical reinforcing members, the vertical members extending above the side walls of the shells, a core of plastic waterproof material filling the space between the shells and a lid composed of an inner shell and an outer shell, the margins of the outer shell extending

down around but being spaced from the edge of the inner shell, the upwardly projecting ends of the vertical reinforcing members of the body being adapted to project into said space when the lid is placed upon the body, and an intermediate 5 core of waterproof plastic material disposed between the outer and inner shells of the lid and extending down between the margins thereof whereby said core of plastic material in the lid will receive and surround the projecting ends of 10 the vertical reinforcement of the body and thus lock the body and lid integrally together.

JAMES W. PRINCE.
